UNITED STATES PATENT OFFICE.

WILLIAM T. MACDONALD AND BARTON W. SCOTT, OF SAN JOSE, CALIFORNIA, ASSIGNORS OF TWO-THIRDS TO SAID MACDONALD AND ONE-THIRD TO SAID SCOTT.

ATTACHMENT FOR TYPE-WRITERS AND OTHER MACHINES.

1,262,819.

Specification of Letters Patent. Patented Apr. 16, 1918.

Application filed April 13, 1917. Serial No. 161,720.

To all whom it may concern:

Be it known that we, WILLIAM T. MACDONALD, a subject of the King of Great Britain, and BARTON W. Scott, a citizen of the United States, both residents of San Jose, in the county of Santa Clara and State of California, have invented a new and Improved Attachment for Type-Writers and other Machines, of which the following is a full, clear, and exact description.

Our invention is applicable to key-operated machines generally, such as typewriters, type-setting machines and the like, in which a carriage is caused to travel and then re-

turn to the initial point.

More particularly, the invention relates to means for automatically returning the carriage by a spring motor in which power is stored by the operation of the keys and incidental to the normal functions of the keys in performing the operations of printing, spacing or the like.

The invention is characterized by novel operations to effect automatically line spacing of the machine preliminary to the automatic return of the carriage under the power of the spring motor.

The invention is characterized also by a drum from which a cord or equivalent flexible element runs over suitable guides and connects with the carriage so as to be paid out from the drum as the carriage advances and to be wound up to return the carriage, the drum being freed from the action of the spring motor for the paying out of the cord and subjected to the action of the motor for the winding up of the cord, and the connection of the cord with the carriage is through the medium of a line spacing lever to cause the operation of the latter as a preliminary to the return of the carriage.

The invention is further distinguished by novel means for controlling and releasing the power shaft of the motor so that it will be held stationary during a forward movement of the carriage and released to effect the return of the carriage.

Characteristic features of the invention also reside in novel trip mechanism comprising elements directly associated with the spring motor, its shaft, etc., and coacting trip elements associated with the carriage to travel therewith so that the tripping will

be automatically and unfailingly brought about at the proper time considering the travel of the carriage.

The invention is furthermore distinguished by various novel features of the trip mechanism as will clearly appear as the description proceeds.

Reference is to be had to the accompanying drawings forming a part of this specification in which similar reference characters indicate corresponding parts in all the views.

Figure 1 is a rear elevation of a typewriting machine showing one embodiment and application of our invention;

Fig. 2 is a plan view largely diagrammatic of the machine illustrated in Fig. 1;

Fig. 3 is an end elevation of the typewriting machine equipped with our invention;

Fig. 4 is a detail vertical section of the spring motor and certain controlling and trip means, the section being taken longitudinally of the motor and in a plane transversely of the typewriter;

Fig. 5 is a plan view of the devices shown in Fig. 4;

Fig. 6 is a vertical section on the line 6—6, Fig. 4;

Fig. 7 is an end view as indicated by the line 7—7, Fig. 4;

Fig. 8 is a detail end view of the carriage and spacing lever controlled by the spring motor.

As stated the invention may be embodied in various machines having a bank of keys acting to operate levers or the like, the movements of which may be utilized to actuate devices for storing up power in the spring motor. We have conventionally shown in the present example certain parts of a typewriter, including keys 10 (Fig. 3) which may in this instance be considered as printing keys and a spacing key, which will operate through different instrumentalities in different machines to perform various work. As here shown each key has a lever 11 suitably fulcrumed as at 12, and a vertically rockable lever 13 is shown, and in practice, arranged in any suitable way to be given movement by the operation of any of the keys. The machine may be of the type in which a longitudinal bar 15 is acted upon by the several key levers 11 to insure the operation of the lever 13. The parts referred to

may be as shown or may have any of the various forms and arrangements found in different makes of typewriters and other machines, whereby a movement of a key will 5 actuate a lever 13 or equivalent means to give rocking movement to a shaft 14. The numeral 16 indicates a typewriter carriage; 17, the platen roller thereof; and 18, a line spacing bar. The numeral 19 indicates the 10 usual spring barrel of typewriting machines, and 20 the strap connecting the same with the carriage as usual.

In our invention the rocking movement imparted to the shaft 14 through the keys as 15 explained, serves to wind a motor spring, there being for the purpose a rocker arm 21 on the shaft 14 and extending beneath the free end of a lever 22 carrying a pawl 23, engageable with a ratchet wheel 24 which is 20 engaged in practice also with a second holding pawl or dog 25 (Fig. 1). The lever 22 is loose on a shaft 26 on which the ratchet wheel 24 is also loose. In fixed relation to the ratchet wheel 24 to turn therewith is the 25 housing 27 of a spring 28, the outer end of which is connected with said housing while the inner end of said spring is connected with a hub 29 secured to the shaft 26 which turns in suitable bearings 30.

30 Loose on the shaft 26 is a drum 31 on which winds a cord or other flexible element 32 that runs over suitable guide pulleys indicated at 33 (Figs. 1 and 2) and has connection with the carriage 16, to return the 35 latter under the force of the spring 28.

The connection between the cord 32 and the carriage 16 is through the medium of a spacing lever 34, best shown in Fig. 8, which is rockably mounted as at 35. Integral with the spacing lever 34, or otherwise made to rock therewith, is an arm 36 which is adapted to press against the line spacing bar 18 of the typewriter, said bar being in the present instance under the influence of a retractile spring 37 of known form.

It is to be noted that the lever 34 is not to be confounded with the usual manually controlled line-spacing lever but is pivoted 50 at its forward end and extends rearwardly so that its free end which is connected with the cord 32 is at the back of the machine. Also it will be noted that the lever 34 acts directly through its arm 36 against the 55 spacing bar 18 to slide the latter.

In order to control the drum 31 to permit it to freely turn as the carriage advances and to cause it to turn with the shaft as the latter is turned by the spring motor, the 60 following means is employed in the illustrated example. A fixed ratchet ring or annular rack 38 is suitably secured as to fixed brackets 39 and we provide a pawl or pawls 40 engaging the teeth of the fixed rack 38 65 during the forward movement of the car-

riage, but shiftable to engage a ratchet wheel 41 in fixed relation to the drum 31 to return the carriage.

The pawls 40 are carried on a post 42 which extends from a shaft 43 in the shaft 70 26 at one end of the latter and co-axial therewith, said shaft 26 being tubular at the said end to receive the shaft 43. One pawl 40 may be carried directly on the post 42 while the other, as shown, is carried on 75 an arm 40^a on said post. The outer end of the shaft 43 has a head 44 and said shaft passes through an eye pin 45 which extends upwardly into a segment 46 having an arcuate slot 47 receiving said pin. The segment 80 46 is on an arm 48 pivotally secured by a vertical pin or shaft 49. The character 30^a represents bearings for the shaft 49. The shaft 49 carries at its upper end a bellcrank lever 50 to one arm 51 of which one end of 85 a pitman 52 is secured. The opposite end of said pitman is connected with one end of a retractile spring 53, the opposite end of said spring being secured to any fixed part of the machine, there being indicated for the 90 purpose a fixed post or pin 54. The other arm 55 of the bellcrank lever 50 is formed at its free end with a vertical trip member 56, the upper free end of which lies adjacent to a rock bar 57, Figs. 1, 2 and 3, 95 mounted on the carriage, 16, to travel therewith. The bar 57 has side arms 58 rockably mounted as at 59, between the ends thereof, on any convenient member 60 of the carriage. The arms 58 beyond their pivot 100 are formed with forks or sockets 61 receiving the ends 62 of rocker arms 63 on a shaft 64 which also is rockably mounted in suitable bearings 65 on the carriage. The shaft 64 has a trip arm 66 traveling longitudinally 105 of any fixed member 67 having adjustable thereon, a marginal stop 68, that is to say, the left marginal stop usual with typewriters, and adapted to be positioned to determine the end of the line. We form the 110 marginal stop 68 with a V-shaped trip member 69 to be engaged by the trip arm 66 so the latter will ride up said trip member 69 to thereby rock the shaft 64 when the carriage reaches the predetermined end of the 115 line.

As will be clear from Fig. 3, the automatic rocking of the shaft 64 thus brought about will depress the arms 63 of said shaft and owing to the articulation of the arms 63 120 with the lever arms 58 carrying the rock bar 57, the latter bar will be rocked upwardly, the purpose of which is to permit an arcuate movement of the upright member 56 of the bellcrank lever 50. Previous to the engagement of the trip member 66 with the fixed trip 125 69, the carriage will have brought the bar 57 to such a position that a trip member 70 on said bar 57 will have engaged the upright member 56 and will have moved the 130

same and will have carried the bellcrank arm 55 from the left hand dotted position shown in Fig. 2 to the right hand dotted position of said figure. The rocking of the 5 bellcrank lever 50 by the trip 70 will have brought the member 56 close to the bar 57 after said upright member has moved through the necessary arcuate path, and will have so moved the arm 51 of the bellcrank 10 lever as to throw the pitman 52 to a position across the pivotal center 49 of the bellcrank in position for the spring 53 to exert a pull on the connecting rod for giving further movement to the bellcrank 50 and the 15 said movement of the bellcrank 50 under the tension of the spring 53 will take place upon the upward rocking of the bar 57 and the release of the upright member 56 through the rocking of the shaft 64 by the 20 trips 66, 69.

The swinging of the bellcrank 50 will have given a turning movement to the pin 49 and thereby carried the arm 48 and segment 46 through an angle to engage the pin 25 45 on the shaft 43, thereby giving an axial movement to the said shaft 43 whereby the post 42 carrying the pawls 40 will be moved to a position to carry the pawls 40 out of engagement with the fixed annular rack 38 30 and into engagement with the ratchet wheel 41 of the drum 31. The release of the pawls 40 from the rack 38 permits the shaft 26 to be turned by the re-action of the motor spring 28 and the drum 31 will thus be 35 turned to wind up the cord 32 and automatically return the carriage 16. Since however, the connection of the cord 32 with the carriage is through the medium of the spacing lever 34, the initial pull of the 40 spring on the cord 32 will rock the spacing lever 34 to cause the element 36 to move the spacing bar 18, thus effecting the line spacing automatically with the automatic return to the carriage. To restore the parts for the 45 release of the drum 31 and the locking of the shaft 26, the rock bar 57 has a second trip 71 which upon the return of the carriage will engage the upright member 56 of the bellcrank 50 and restore said bellcrank 50 to the left hand position indicated in Fig. 2. It will be observed from Fig. 4 that the 55 upper end of the member 56 is beveled as at 72 and there is a corresponding beveled surface 73 on the bar 57 to permit the return of the member 56 past the said bar. The movement of the bellcrank lever 50 to the original position will have carried the segment 46 in a direction to restore the shaft 43 and post 42 to the original position with 60 the pawls 40 out of engagement with the ratchet wheel 41 of drum 31 and into engagement with the fixed ratchet ring 38 to again hold the shaft 26 against movement for the rewinding of the spring 28 by the 65 lever 22, pawl 23, and ratchet wheel 24. The

purpose of the arcuate slot 47 is to permit a material movement of the segment 46 and bellcrank lever 50 by the trips 70, 71 without affecting the pin 45 and shaft 43 so that the final movement of the segment 46 by the 70 spring 53 will actuate the shaft 43.

With typewriters as now generally constructed, the return of the carriage is arrested by impact of metal against metal which necessarily results in noise and jars 75 the machine as well as the nerves of the operator. In order to overcome the objection of metallic contact we provide cushions 74, 75 preferably of soft rubber on an end of the carriage and on the machine so that 80 in the impact and stopping of the carriage, the noise and jar are entirely eliminated.

We wish to state in conclusion that although the illustrated example constitutes a practical embodiment of our invention we 85 do not limit ourselves strictly to the mechanical details herein illustrated, since manifestly the same can be considerably varied without departure from the spirit of the invention as defined in the appended 90 claims.

Having thus described our invention we claim as new, and desire to secure by Letters Patent:

1. In a machine of the class described, the 95 combination with a carriage thereon, and a transversely slidable spacing bar on the carriage, of a lever pivoted at its front end and extending to the rear of the carriage, a member on the said lever directly bearing 100 against the said spacing bar, a motor, and means connected with the said lever, and adapted to be actuated by the motor, to rock the said lever and through the medium of the lever to impart a return movement to the 105 carriage.

2. In a machine of the class described having a carriage; a spring motor, means to wind said motor during a forward movement of the carriage, a drum, a flexible element connected with the drum and with the carriage, means to cause the motor to turn the said drum for returning the carriage, controlling means for the motor and drum and shiftable to cause winding of the motor 110 and release of the drum during a forward movement of the carriage and effect driving connection between the motor and drum for return of the carriage, and trip mechanism to shift said controlling means, said trip 115 mechanism including trip means adapted to engage the controlling means, as well as trip means traveling with the carriage to actuate the first trip means, and relatively fixed trip means on the machine to engage the trip 120 means on the carriage.

3. In a machine of the class described comprising a carriage, a spring motor, a drum, and means connecting the carriage with the drum; the herein described, controlling 130

means for the motor and drum including a ratchet wheel turning with the drum, a pawl subject to rotary movement by the motor, means to engage the pawl with the ratchet wheel and revolve the engaged pawl and ratchet wheel to cause the drum to return the carriage, and means operable by the return of the carriage to disengage the pawl from the drum and lock the pawl against movement by the motor:

4. In a machine of the class described, having a carriage, a drum, a flexible element connected with the carriage and adapted to be wound upon the drum to return the carriage, and to unwind as the carriage moves forward, a shaft on which the drum is loose, a motor spring on the shaft, means to wind the spring to store power therein during a forward movement of the carriage, a ratchet wheel on the drum, a shaft co-axial with the first shaft and adapted to turn therewith and to slide, a pawl carried by the second shaft and movable into and out of engagement with the ratchet wheel on the drum by the sliding of the said second shaft, relatively fixed means to hold the pawl from movement when disengaged from the drum, controlling means connected with the second shaft to slide the same and shift the pawl, and trip mechanism for the controlling means, said trip mechanism including trip means on the carriage, means to trip said controlling means by said means on the carriage, and coacting trip means on a relatively fixed part of the machine to engage the trip means of the carriage.

5. An attachment for machines of the class described having a carriage, said attachment including a motor spring, a shaft on which said spring is mounted, a ratchet wheel connected with the spring to wind the same, means to actuate the ratchet wheel, a drum loose on the shaft, means to connect the

drum with the carriage to return the latter, a ratchet wheel on the drum, a fixed annular rack adjacent to the ratchet wheel of the drum, a pawl, an element between the drum and fixed rack and carrying said pawl, said element being shiftable to carry the pawl to positions to engage the ratchet wheel of the drum or the fixed rack, a shaft co-axial with the first shaft and secured to said element, a pin having an eye embracing said second shaft and adapted to shift the latter, and means to move said pin in opposite directions, said means being controlled by the movements of the carriage.

6. In a machine of the class described comprising a carriage, a spring motor, a drum, and means connecting the carriage with the drum; the herein described controlling means for the motor and drum including a ratchet wheel turning with the drum, a fixed annular rack adjacent to the ratchet wheel of the drum, a pawl, an element between the drum and the fixed rack and carrying said pawl, said element being shiftable to carry the pawl to positions to engage the ratchet wheel of the drum or the fixed rack, a shaft coaxial with the drum and secured to said element, a pin having an eye embracing said shaft adapted to shift the latter, a pivoted member having a segmental slot receiving said pin, an upright shaft on which said slotted member is mounted, a bellcrank lever on said upright shaft, a retractile spring, means connecting one end of the spring with an arm of the bellcrank, the opposite end of the spring being relatively fixed, an upright trip member on the second arm of the bellcrank, and coacting trip means governed by the movements of the carriage to engage the said upright trip member.

WILLIAM T. MACDONALD.
BARTON W. SCOTT.
